UNITED STATES PATENT OFFICE.

THOMAS SPRIGGS, OF MITCHELL, KANSAS.

LOCK-HINGE.

SPECIFICATION forming part of Letters Patent No. 395,086, dated December 25, 1888.

Application filed January 31, 1888. Serial No. 262,486. (No model.)

To all whom it may concern:

Be it known that I, THOMAS SPRIGGS, of Mitchell, in the county of Rice and State of Kansas, have invented a new and useful Improvement in Door-Checks, of which the following is a full, clear, and exact description.

This invention relates to door-checks for holding doors open, and has for its object to provide a door-check whereby a door may be securely held open at different distances. The invention consists in a door-check for this purpose constructed and arranged as herein-after described and claimed.

Reference is to be had to the accompanying drawings, forming a part of this specification, in which similar letters of reference indicate corresponding parts in all the figures.

Figure 1 illustrates the door-check with covering-plate removed applied to a door and frame broken away. Fig. 2 is a horizontal section thereof on line xx , Fig. 1. Fig. 3 is a central vertical section thereof. Figs. 4, 5, and 6 are detail views of parts detached and broken away.

In the construction of this device a bolt, 1, formed with an enlarged portion, 2, having a number of sides, 3, is employed, located in the enlarged portions 4 5 of the straps 6, the enlarged portion 7 of strap or bar 8, and the enlarged portion 9 of strap or bar 10.

The door 11 and frame 12 are cut away to permit of the parts being placed in position and the straps 6 8 10 fastened by screws 13. To the bolt 1, cut away, as at 14, is pivoted the forked end 15 of a lever, 16, having an oval open portion, 17, in which is located cam 18, mounted on the end of a rod, 19, passing through slot or hole 20 in door 11 and provided with an opening-handle, 21.

The lever 16 is formed with an arm, 22, having a slot, 23, loosely mounted on a pin, 24, in plate 25, which is held in place by the screws 13 and covers the lever 16 and cam 18. The straps 6 are covered by a plate, 26, held in place by screws 13.

The enlarged portions 4 and 9 are formed with round openings 27, in which the bolt 1 may slide or turn, while the enlarged portions 5 and 7 are formed with openings 28, adapted in shape to the enlarged portion 2 of the bolt

1 and permitting the latter to slide therein, but not to turn. In this way it will be seen that when the enlarged portion 2 of said bolt engages openings 5 and 7, as in Fig. 3, the door cannot turn on its hinges, but that when the portion 2 is raised clear of portion 5 then the door 11 is free to move.

In operating this device, the bolt 1 being in the position shown in Fig. 1, the door is opened the desired distance, when the portion 2 of bolt 1 will register with opening 28 in enlarged portion 5, and upon turning the handle 21 the cam 18 will act upon lever 16 to slide bolt 1 downward and throw enlarged portion 2 into engagement with opening 28, thereby locking the door securely in the desired open position. The enlarged portion 2 and the opening 28 may be of such shape or with as many corresponding sides as to lock the door at any angle desired.

While a specific construction of parts has been set forth, I do not intend to limit myself thereto, as the bolt 1 may be operated by other mechanism than that shown, and the locking parts may be of different form to accomplish the same result. The invention broadly covers a vertically-sliding reciprocating bolt and operating mechanism mounted on a door and a socket mounted on the door-frame, the sliding bolt being adapted to be thrown into and out of engagement with the socket to hold a door located locked in different open positions.

Having thus described my invention, what I claim as new, and desire to secure by Letters Patent, is—

1. A door-check to hold doors in different open positions, consisting of a socket-piece mounted on the door-frame and a socket-piece mounted on the door, in combination with a vertically-sliding bolt having locking projections adapted to engage the socket-pieces and a lever for operating the bolt, substantially as described.

2. A door-check to hold a door in different open positions, consisting of socket-pieces attached, respectively, to the door and door-frame and a vertically-sliding bolt having an irregular enlarged portion, in combination with straps secured on the door and door-frame,

- having irregular openings therein adapted to register with each other as the door is moved and through which the bolt passes, substantially as described.
- 5 3 The combination, with straps 10 and 8, secured to door 11 and having enlarged portions 9 7, with sockets 27 28, and straps 6, secured to door-frame 12 and having sockets 27 28, of bolt 1, having enlarged portion 2, with 10 sides 3 and lever 16, having opening 17, cam 18, rod 19 in socket 20, handle 21, and covering-plates 25 26, substantially as described.
4. A door-check consisting of a vertically-sliding locking-bolt having a projection thereon and a lever and operating-handle located on the door, in combination with socketed straps having irregular openings therein, through which said bolt passes, substantially as described. 15

THOMAS SPRIGGS.
